PROCESS OF MANUFACTURING POWER-GAS.

No. 841,499.

Specification of Letters Patent.

Patented Jan. 15, 1907.

Application filed November 30, 1904. Serial No. 234,933.

To all whom it may concern:

Be it known that I, EMIL FLEISCHER, doctor of philosophy, chemist, residing at 32 Tiergartenstrasse, Dresden-Strehlen, Kingdom of Saxony, German Empire, have invented certain new and useful Improvements in Processes of Manufacturing Power-Gas, of which the following is a specification.

This invention relates to that class of processes for the manufacture of power-gas in which air is drawn into a gas-generator from above and from below while the combustible gas produced is drawn off laterally through an exhaust-pipe opening into the apparatus about midway of its height, and has for its object to enable the employment in such gas-generators of bituminous fuels, lignite, sawdust, and other combustible materials the use of which has hitherto been deemed impracticable for power-gas manufacture.

The direct production of a gas free from tar-vapors and other easily-condensable products presents difficulties which it has been sought to overcome in various ways. One expedient which has been resorted to consists in placing the internal orifice of the exhaust-pipe at such a low level that the hydrocarbons produced have to percolate in their passage to the exhaust through an incandescent stratum of fuel, whereby they undergo decomposition.

According to the improved process which constitutes this invention the object is attained according to a procedure different from that above referred to, based on the employment of a method of conducting or controlling the changes which are caused to take place in the upper region of the gas-generator, whereby the hydrocarbons suffer decomposition or combustion immediately on their formation, the particular manner in which the air is supplied being instrumental in the proper conduct or control of the said changes.

In the case of so-called "suction gas-generators" it has been the practice to admit the air in such manner that it is constrained by suction to enter the generator from above, passing through the whole upper surface of the charge of fuel presented to it and also from below. According to the present invention, however, the air is caused to act on

the fuel at a third point, with the object of bringing about the combustion at this point 55 of the tar-vapors and other products resulting from the combustion in the uppermost part of the generator.

It has been found that when the air is simply admitted to the whole upper surface complete combustion of the hydrocarbons produced cannot be effected, because these products, so to speak, always travel in front of the air supporting the combustion, and consequently altogether escape being acted upon 65 by the latter.

In consequence of the conditions I have specified, which obtain in generators as heretofore in use having a simple undivided upper air-supply, the tar-vapors, since they 70 cannot be burned, must be decomposed by passage through incandescent coke.

According to the present invention these deleterious products of the fuel—viz, the tar-vapors—are burned at a third point, to which 75 air is led, whereby the requisite quantity of air must be supplied from a central position outwardly in the manner hereinafter specified.

In suction gas-generators of the type specified the gases are exhausted or withdrawn through an annular channel on about the level of the middle height of the charge, which remains unobstructed, debouching into an inclined channel which extends 85 downwardly and inwardly toward the charge so that all the gas generated is free to escape by way of the inclined channel into the annular channel to the main, which is connected to the latter. On account of this lateral 90 exhaustion of the gases it is necessary that the air should be supplied to the generator approximately along its vertical axis, so as to pass to the center of the charge in order that it shall with certainty traverse not only 95 the lateral but also the central portion of the charge, for if the air were supplied peripherally it would simply pass close along the walls of the generator, so that the central column of combustible material would remain untraversed by it; but, further, not only must the "secondary" air-supply (by which I mean the air supplied to the above-mentioned third point of entry) be central, but this air must also impinge on the combustible at a point somewhat beneath its

100
105

surface, so as to come into contact with the "flank," so to speak, of the tar-vapors, and thereby effect the combustion of the latter in a satisfactory manner. This object may be attained in various manners. The simplest expedient is to provide an air-pipe (preferably cooled) extending from above downward to a greater or lesser depth in the combustible stratum; but it has been found more practicable to employ instead of this pipe a ring either open or furnished with a protective roof. This ring should be of such a width that the coal or coke lying beneath its lower margin may in taking up its natural angle of inclination form a wide funnel or crater thereunder into which the secondary air may freely enter.

By the time that the fuel arrives in the vicinity of the lower margin of the ring it will have lost its gases and vapors, so that the crater already offers to the secondary air a strongly-degasified combustible. Now this is important, because a very high temperature is produced in the crater by the introduction thereinto of the secondary air, and therefore also the air for the combustion of the tar-vapors which it encounters is strongly heated preliminarily. By adjusting the ring to a higher or lower position the zone of the secondary air, and thereby its action on the fuel, may be varied at will.

A gas-generator suitable for carrying out the process is illustrated in the accompanying drawing, which shows a central vertical section of the apparatus.

a is the body of the apparatus, provided with a grate *b* and an air-supply pipe *c*, as usual, and in the present case with a water-supply or an evaporating-dish *d* and with an ash-hole *f*.

The power-gas is drawn off through the pipe *g*, either by means of a special exhaust-pump or by the motor itself, from the annular channel *h*, which occupies a position in the generator above the conical slope of the combustible.

In the upper part of the generator the ring *m* is so set as to allow of its height being adjusted, and it is closed by a roof *n* and furnished with lateral slits *p*, (above the level of

the freshly-introduced coal,) through which the air can gain access to the interior of the ring. The fuel is supplied to the space *q* around the ring, this space being left open at top, so that the air has access to the fresh fuel from above only, this arrangement allowing of the easy breaking up of fuel which tends to cake together.

Beneath the lower edge *r* of the ring is formed the funnel-shaped crater *s*, into which the secondary air enters, passing through the fuel and burning the products of combustion and distillation produced in the upper part of the same to form fixed gases, which latter in traversing thereafter the glowing coke are for the most part transformed into carbon monoxide and hydrogen, (together with nitrogen.) It will be evident that this arrangement may be variously modified. For example, a pyramidal grate may be provided whose bars extend as far upward as the upper stratum of fuel.

Now what I claim, and desire to secure by Letters Patent, is the following:

1. In the process of manufacturing power-gas from bituminous fuel and the like with top and bottom air-supply and exhaust of the gases at the mid-height of the charge, the auxiliary step of supplying an additional body of air below the point at which the top air-supply takes place and in or in the neighborhood of the vertical axis of the charge.

2. In the process of manufacturing power-gas from bituminous fuel and the like with top and bottom air-supply and exhaust of the gases at the mid-height of the charge, the auxiliary step of forming a free crater of the charge in the axis of the generator and beneath the upper surface of the charge and supplying air to this crater in addition to the main top and bottom supply.

In testimony that I claim the foregoing as my invention I have signed my name, in presence of two witnesses, this 21st day of November, 1904.

EMIL FLEISCHER.
